CLAIM

The ornamental design for a bird feeder stand, as shown and described.

DESCRIPTION

FIG. 1 is a top and side perspective view of the bird feeder stand showing my new design; FIG. 2 is a side view thereof, all other sides being of identical appearance; and, FIG. 3 is a top plan view thereof. FIGS. 1 and 2 are shown broken away for convenience of illustration and to show indeterminate length.

FIG. 1

FIG. 2

FIG. 3
